UNITED STATES PATENT OFFICE.

EDWARD POSSON, OF ST. PAUL, MINNESOTA, ASSIGNOR OF ONE-HALF TO
ALFRED LOVELL, OF ST. PAUL, MINNESOTA.

CAR-BRAKE.

SPECIFICATION forming part of Letters Patent No. 714,236, dated November 25, 1902.

Application filed June 17, 1902. Serial No. 112,042. (No model.)

To all whom it may concern:

Be it known that I, EDWARD POSSON, a citizen of the United States, residing at St. Paul, in the county of Ramsey and State of Minnesota, have invented certain new and useful Improvements in Car-Brakes; and I do hereby declare the following to be a full, clear, and exact description of the invention, such as will enable others skilled in the art to which it appertains to make and use the same.

My present invention relates to air-brake systems, and has for its object to provide an independent hand-brake therefor.

To this end the invention consists of the novel devices and combinations of devices hereinafter described, and defined in the claims.

In the standard air-brake systems now in general use hand-brakes—that is, hand-actuated connections for setting the brakes of the air-brake systems—are employed; but the arrangement is such that the hand-brake connections serve as a base of reaction for the air-brake connections, and vice versa. From this arrangement many bad results follow. For instance, suppose both the air-brake and hand-brake connections to be set and the train to be starting down a long grade. It will frequently happen that leakage from the air-brake cylinder will cause the air-brake connections to release their tension, and when this takes place it of course follows that the brake-shoes will be released, since they are not independently held by the hand-brake connections. Again, the release of the brakes by leakage from the brake-motor will permit a train left standing on a grade to run away. Many serious accidents have resulted from this cause. Again, the releasing of the air-brake connections will always release the hand-brake connections, and vice versa. In short, this interdependence of action between the air-brakes and the hand-brake devices in many ways tends to render the braking system unreliable and under many conditions ineffective.

In accordance with my invention I provide hand-brake connections which do not serve as a base of reaction for the levers or connections of the air-brake system and which may be operated independently thereof. More specific-

ally stated, in view of my improved arrangement the brakes may be set either from the brake-motors or from the hand-brake connections or hand-power device, or simultaneously from both, and the releasing of the tension either from said motor or from said hand-brakes will not in itself release the brakes, but will leave the same set under tension from the power device which is not to be released.

My invention is illustrated in the accompanying drawings, wherein like characters indicate like parts throughout the several views.

Figure 1 is a skeleton view, principally in perspective and partly in side elevation, showing the air-brakes and the independent hand-brake connections incorporated into the system. Fig. 2 is a side elevation showing the improved brake connections applied to a car, parts being broken away. Fig. 3 is a detail in section, taken approximately on the line $x^3 x^3$ of Fig. 2. Fig. 4 is a section on the line $x^4 x^4$ of Figs. 3 and 6. Fig. 5 is a detail with parts broken away, showing one of the truck-lever connecting-links and supporting-guide thereof; and Fig. 6 is a plan view showing a portion of the brake connections, the position of the car-body being indicated by dotted lines.

The numeral 1 indicates the car-body, and 80 the numeral 2 the car-trucks, having wheels 3.

The numeral 4 indicates the air-brake motor, supported, as usual, from the car-body 1.

The numeral 5 indicates the brake-shoes carried by the brake-beams 6, which brake-beams are supported in the ordinary or any suitable way by hangers 7, pivotally depending from the truck-frames 2.

The following elements, which afford connections between the brake-motor 4 and the 90 brake-beams 6, are of standard or ordinary construction, and hence the following brief description thereof will suffice for the purposes of this case.

The numeral 8 indicates the cylinder-levers, 95 connected by cylinder-lever rods 9.

The numeral 10 indicates the air-brake floating levers, connected to said levers 8 by rods 11.

12 indicates fulcrum-levers pivoted to a 100 fulcrum-bracket 13 and connected to the floating levers 10 by connecting-rods 14.

15 indicates the truck-levers, which are connected to the fulcrum-levers 12 by rods 16 and to the inner brake-beams 6 by links 17.

The numeral 18 indicates the equalizing-levers, connected to the truck-levers 15 by a sliding link 19, which link is supported by a slotted supporting-bracket 20 and a roller-equipped hanger 21, the latter of which is shown in Fig. 5 and both of which are supported by the same truck-frame 2.

22 and 23 indicate lever-supporting brackets, which, as well as the fulcrum-bracket 13, are supported from the bottom of the car-body.

15 The numeral 24 indicates the hand-brake connecting-rods, which at their outer ends are provided with stops 25 and work freely through the stop-brackets 26, rigidly secured on the car-body 1 in the ordinary way.

20 The numeral 27 indicates a hand-wheel and staff connected to the outer end of the adjacent rod 24 by a chain 28.

If the inner ends of the hand-brake connecting-rods 24 were to be connected to the 25 ends of the air-brake floating levers 10, the ordinary standard construction would be thereby provided. However, in carrying out my invention a very different arrangement is provided, which in its preferred application is 30 as follows: The ends of the said air-brake floating levers 10 are fulcrumed in a fulcrum-bracket 29, which is rigidly secured to the bottom of the car-body 1. The free ends of the levers 10 are provided with depending 35 studs 30, which work in the slots 31 of the said fulcrum-bracket 29, and the said bracket is bifurcated, as best shown in Fig. 4, to afford a longitudinal slot in which the free end of the lever 10 freely slides. The obvious 40 purpose of the fulcrum-bracket 29 is to permit the brake-motor to release while the brakes are set by the hand-brake devices. When the fulcrum pin or stud 30 strikes the inner extremity of the slot 31 of said bracket 45 29, it affords a fulcrum and the bracket 29 a base of reaction for the lever 10.

The inner ends of the hand-brake connecting-rods 24 are connected to the free ends of the hand-brake floating levers 32, the other 50 ends of which are shown as pivotally connected to the inner ends of the same connecting-rods 14 to which the levers 10 of the air-brake are connected. The two hand-brake floating levers 32 are connected by a long 55 connecting-rod 33.

The action of the brake mechanism above described is as follows: Under the action of the air-brake motors 4 the brakes may be set in the ordinary way, except that the floating 60 levers 10 instead of finding their base of reaction through the hand-brake connections react directly against the fulcrum-brackets 29. It is evident that when the brakes are thus set from the motor they do not set the 65 hand-brake connections or put the same under strain. It is also evident that the brakes may be set from the brake-motor regardless

of whether or not the hand-brake connections are tightened and, in fact, may be set even though the hand-brake connections should 70 be out of repair or even entirely removed.

It is also evident that when one of the hand-brake connecting-rods 24 is drawn outward by the hand-wheel and staff 27 turned so as to wind up the chains 28 the hand-brake 75 floating levers 32 will be put under strain (the connecting-rod 33 serving as a fulcrum for both of the same) and through the so-called "air-brake" connections, beginning with the connecting-rods 14, the brakes will 80

be set in the same manner as when the brake-motor is actuated. The brakes may be set from the hand-operated power device or connection at either end of the car, and it will of course be understood that all of the brakes 85 of the car are thrown into action by the manipulation of a single power device.

It is further evident that even though the brakes are set from the brake-motor under a strain much greater than that which can be applied 90 to the same by the hand-power devices or

brake connections still additional pressure may be applied to the brakes by tightening up one or both of the hand-brake devices. This is not the case in prior systems, wherein 95 the hand-brake connections afford a base of reaction for the air-brake connections. It is further evident that should the brakes be applied by power exerted both by the brake-motor and by the hand-power devices and 100 the one thereof be released the other will remain active to hold the brake set. Hence it

of course follows that if going down a long grade or standing on a grade, the brake should be set both by the hand-motor and the hand-power devices, the hand-power devices will hold the brake set, even though the air should leak from the brake-motor, so as to render 105 the said motor inefficient. In running long mountain-grades this is very important, as it 110 frequently happens that the auxiliary cylinders must be recharged from the main reservoir before the bottom of the grade is reached.

In order to reset the air-brakes and in order to accomplish this recharging of the auxiliary reservoirs, it has hitherto been necessary 115 to release the brakes.

It will of course be understood that the brake mechanism above described is capable of many modifications within the scope of my 120 invention. Hence it may of course be incorporated in brake mechanism for four-wheeled trucks, as well as for six-wheeled trucks.

What I claim, and desire to secure by Letters Patent of the United States, is as follows: 125

1. In an air-brake system, the combination with a brake-motor having connections for actuating the brake-shoes, of hand-actuated brake connections extending from the opposite ends of the car involving a pair of 130 levers forming no part of the connections between said motor and the brake-shoes, but attached to said air-brake connections on the opposite sides of the cylinder-lever and

operating thereon to set the brakes independently of the said motor, and a rod connecting said two levers and rendering the same simultaneously operative, substantially as described.

2. In an air-brake system, the combination with a brake-motor having connections for actuating the brake-shoes involving a pair of fulcrumed levers, of an independent hand-brake connection involving a pair of floating levers and pivotally connected on the opposite sides of the cylinder-levers to the same parts to which said fulcrumed levers are pivoted, a connecting-rod extending between said two floating levers, and hand-power devices at the opposite ends of the car connected one to each of said floating levers, said parts operating substantially as described.

3. In an air-brake system, the combination with a brake-motor having connections to the brake-shoes involving the fulcrumed levers 10, of the fulcrum-brackets 29 to which said levers 10 are fulcrumed with freedom for slid-

ing movements in the brake-releasing action, of hand-brake connections involving a pair 25 of floating levers connected to the intermediate elements of the air-brake connections, connecting-rod extending between said floating levers, and hand-power devices at the opposite ends of the car connected one to each 30 of said floating levers, said parts operating substantially as described.

4. In an air-brake system, the combination with a brake-motor having connections to the brake-shoes involving the cylinder-levers 8, 35 and intermediate levers 10 and 12 and connecting-rods 11 and 14, of hand-brake connections involving the floating levers 32 pivoted to the connecting-rods 14 and connected by the rod 33, substantially as described. 40

In testimony whereof I affix my signature in presence of two witnesses.

EDWARD POSSON.
